UNITED STATES PATENT OFFICE.

FREDERICK KOECHEL, OF NEW YORK, N. Y.

SPRAYING APPARATUS.

No. 838,193.

Specification of Letters Patent.

Patented Dec. 11, 1906.

Application filed April 19, 1906. Serial No. 312,641.

To all whom it may concern:

Be it known that I, FREDERICK KOECHEL, a citizen of Germany, residing at New York city, Manhattan, county and State of New York, have invented new and useful Improvements in Spraying Apparatus, of which the following is a specification.

This invention relates to an improved spraying apparatus more particularly designed for steaming the face and for similar purposes.

In the accompanying drawings, Figure 1 is side elevation of my improved spraying apparatus; Fig. 2, a detail of the steam-valve, and Fig. 3 a detail of the ring supporting the liquid-receptacle.

The spraying apparatus consists of a fo-
raminated cylindrical shell 4, removably se-
cured to a base 5 by pin 6 and bayonet-slot 7.
The shell 4 contains a lamp 8 and supports a
steam-boiler 9, having a bead 10, that rests
upon the upper edge of the shell. Within an
upper flanged opening of the boiler is fitted a
threaded ring 11, into which is screwed a
threaded valve-casing 12, having a steam
service-port 13 and a diametrically-arranged
exhaust-port 14. Within a tapering bore of
casing 12 is fitted a conical valve-plug 15,
having an angular duct 16, that may be made
to register with either of the ports 13 or 14.
The plug 15 has a slight vertical play within
casing 12, so that it will be raised by excess-
ive steam-pressure and act as a safety-valve.

Normally the plug is held to its seat by a
coiled spring 17, surrounding its lower re-
duced end and inclosed within a chamber of
casing 12. The upper end of the spring bears
against a shoulder 18 of the casing, while its
lower end bears against a nut 19, fitted upon
the lower threaded end of the plug. By ad-
justing this nut the tension of spring 17, and
consequently the steam-pressure in the boiler,
may be regulated. If the pressure exceeds
the limit desired, the plug 15 will be slightly
raised against action of spring 17, and the
steam will thus escape between the plug and
casing. The port 13 communicates with a

steam-pipe 20, having steam-nozzle 21. From
pipe 20 depends a curved arm 22, the lower
free end of which carries a nut 23. This nut 50
engages the threaded stem 24 of a liquid-noz-
zle 25, to the lower end of which is connected
a flexible tube 26, having at its bottom a per-
forated weight 27. The tube 26 dips into a
liquid-receptacle 28, supported upon an open 55
ring 29, the bent ends 30 of which engage a
grooved keeper 31, secured to shell 4.

The nozzle 25 extends at right angles to noz-
zle 21, and by turning it in one or the other
direction it may be raised or lowered, so that 60
the distance between the discharge-orifices of
the nozzles is readily adjustable. This ad-
justment serves to regulate the quantity of
liquid lifted and sprayed by the steam-noz-
zle. The shell 4 has a handle 32, and the 65
plug 15 has a handle 33, by which it may be
turned to direct the steam either to nozzle 21
or to the exhaust-port 14.

What I claim is—

1. A spraying apparatus composed of a 70
shell, a superposed boiler, a valve-casing on
the boiler having a steam-port and an ex-
haust, a vertically - movable and rotatable
spring-valve having a duct that is adapted to
register with said port and exhaust, a steam- 75
nozzle communicating with the steam-port,
and a liquid-nozzle in proximity to the steam-
nozzle, substantially as specified.

2. A spraying apparatus provided with a
shell, a superposed boiler, a valve-casing on 80
the boiler having a steam-port and exhaust,
a vertically-movable and rotatable valve
having a threaded projection, a nut adjust-
ably engaging said projection, a spring en-
gaging the valve-casing and nut, a steam- 85
nozzle communicating with the steam-port,
and a liquid-nozzle in proximity to said
steam-nozzle, substantially as specified.

Signed by me at New York city, Manhat-
tan, New York, this 18th day of April, 1906. 90
FREDERICK KOECHEL.
